(57) **CLAIM**

I claim the ornamental design for a baseball plate charm, as shown.

DESCRIPTION

FIG. 1 is a perspective view illustrating the baseball plate charm with a hoop in ghost;

FIG. 2 is a rear elevational view of the baseball plate charm of FIG. 1;

FIG. 3 is a right side elevational view of FIG. 2;

FIG. 4 is a left side elevational view of FIG. 2;

FIG. 5 is a bottom elevational view of FIG. 2; and,

FIG. 6 is a top elevational view of FIG. 2.
